DESIGN FOR A RAZOR BLADE

William Werner, Belleville, N. J., assignor to Best
Blades Inc., Newark, N. J., a corporation of New Jersey

Application November 9, 1940, Serial No. 96,454

Term of patent 3½ years

To all whom it may concern:

Be it known that William Werner, a citizen of the United States and resident of Belleville, in the county of Essex and State of New Jersey, has invented a new, original, and ornamental Design for a Razor Blade, of which the following is a specification, reference being had to the accompanying drawing forming part thereof, in which,

Fig. 1 is an elevational view of a razor blade embodying my new design; and

Fig. 2 is an end edge view thereof.

I claim:

The ornamental design for a razor blade, substantially as shown.

WILLIAM WERNER.
